UNITED STATES PATENT OFFICE.

CARL W. WEISS, OF BROOKLYN, NEW YORK.

INTERNAL-COMBUSTION ENGINE.

1,261,465.

Specification of Letters Patent.

Patented Apr. 2, 1918.

Application filed March 3, 1916. Serial No. 81,798.

To all whom it may concern:

Be it known that I, CARL W. WEISS, a citizen of the United States, residing in the borough of Brooklyn of the city of New

5 York, in the State of New York, have invented certain new and useful Improvements in Internal-Combustion Engines, of which the following is a specification, reference being had to the accompanying drawing, forming

10 a part hereof.

This invention relates to internal combustion engines in which air is compressed in the crank case.

The principal object of the invention is to 15 provide for the cooling of the pitman and wrist-pin by the inflowing air. The single figure of the accompanying drawing is a view in longitudinal, vertical section of an engine constructed in accordance with the

20 present invention.

The improved engine, of course, has all the usual parts in somewhat the known relationship each to each. The engine frame *a*, which is formed at one end in the shape of 25 a closed crank casing *a'*, is so cast as to receive readily a cylinder liner *b* which is retained fixedly in position by the removable cylinder head *c*. The liner *b* may have formed in its periphery annular shoulders 30 *b'*, or the like, for snug engagement with corresponding shoulders formed in the engine frame. In the cylinder liner *b* is mounted for reciprocation, a trunk piston *d* to which is secured the usual pitman *e* 35 as through a wrist pin *d'*.

The cylinder liner *b* has cast therein at suitable points, two annular series of ports *b²* and *b³*, the first of which series of ports 40 communicates with the exhaust passage *a⁸*, indicated as integral portion of the engine frame *a* and the second of which may communicate with the cooling spaces between the cylinder liner and the engine casing. The ports *b²* and *b³*, just shown, are in juxtaposition to one another so that they are closed and opened, respectively, in quick succession 45 by the piston *d*, for a reason which will appear hereinafter. The engine frame *a* has formed therein an annular series of lugs *a²* 50 which are provided with ports therein and are spaced from one another around the inner face of the engine frame and register, respectively, with a corresponding series of ports *b⁴* formed in the cylinder lining *b*. 55 The lugs *a²* are at such a distance from one

another as to permit free passage of air to and fro therebetween. Each of the ports in each lug *a²* communicates with an air inlet passage *a³* which may be formed with the engine frame *a* and may extend around 60 the engine frame and be opened to communication with the atmosphere through other ports *a⁴* formed adjacent the lower side of the engine. It will be observed that the ports *b⁴* in the cylinder liner are always covered 65 by the piston *d* when the other ports *b²* and *b³* are uncovered and vice versa. The inflow of fresh air through the inlet passage *a³* is controlled further by means of a deflector ring *d²* formed on the rear end 70 of the trunk piston *d* and arranged with baffles by which, upon registration of the ports *d⁴* in the ring with the ports *b⁴* in the liner plate, the air is directed in its travel toward the center of the piston, thereby 75 cooling the wrist pin *d'* and the entire inner face of the piston.

Before describing the operation of the engine it is well to point out that the steam employed with the air is derived from the 80 usual steam dome *a⁶* in the engine frame which, in the present instance, is in communication with the chambers in the water-jacketed cylinder head *c* and supplies steam through a pipe *i* to one of the scavenger 85 ports *b³* from whence it passes into the working chamber *b*. It is also important to note that the forward end of the trunk piston *d* is constructed of such form as to further the realization of the desired objects, being 90 chamfered or of a generally conical form tapering toward the axis of the piston.

In the operation of the improved engine air is drawn in through the ports *d⁴* in the deflector ring *d²* when the piston is at the 95 extreme forward end of its travel and this air, while serving the purpose of cooling the piston and all surrounding parts, is utilized for the explosive mixture itself. During the rear stroke of the piston the entrapped air 100 is forced around the annular cooling spaces between the cylinder liner *b* and the engine frame *a* and immediately upon the uncovering 105 of the annular series of scavenging ports *b³* by the forward end of the piston, rushes through these ports toward the axis of the working chamber *b* along the curved conical face of the piston. Upon the next forward movement of the piston *d* the fresh air left 110 in the cylinder with the steam derived

through the pipe i is forced into the vaporizing chamber f where it mixes with oil introduced through the ports f' . The inflow of fresh air through the ports d^4 to the inner side of the trunk piston d upon each cycle of movements and its subsequent rush along the outer wall of the cylinder liner b through the scavenging ports b^3 insures an adequate cooling of the entire engine at all 10 times.

Minor details of structure may be changed and rearrangements of the parts made, but all such modifications are to be deemed within the spirit of this invention provided

they fall within the scope of the appended 15 claim.

I claim as my invention:

In an internal combustion engine, in combination with air inlet ports, a piston to control the inflow of air through the ports and 20 a deflector ring provided with baffles carried on the open end of the piston whereby when the inlet ports are overrun air is directed into the piston to cool the piston and wrist pin.

This specification signed this 1st day of March, A. D. 1916.

CARL W. WEISS.
